UNITED STATES PATENT OFFICE.

MICHAEL WALSH, OF DENVER, COLORADO.

FROGLESS SWITCH.

1,425,619.

Specification of Letters Patent. Patented Aug. 15, 1922.

Application filed July 2, 1920, Serial No. 393,658. Renewed April 4, 1922. Serial No. 549,501.

To all whom it may concern:

Be it known that I, MICHAEL WALSH, a citizen of the United States, residing in the city and county of Denver and State of Colorado, have invented a new and useful improvement in frogless switches for use by railroads or wherever it becomes necessary to switch from one line of trackage to another upon a permanent way, of which the following is a full and complete description and specification, reference being had to the accompanying drawings, which are hereby made a part thereof.

This invention relates to that class of switches wherein the passage from one line of rails to another is effected wholly by the movement of certain elements of the rail-way itself, and without the intervention of frogs, points or guard-rails, as they are generally employed in all present devices and installations.

The objects and purposes of this invention are:—to provide a device whereby a switch may be made and operated without the elements of frogs, points or guard-rails; to simplify and improve the construction, operation and maintenance of switches generally, thereby reducing the cost, without in anywise interfering with the safety or certainty of their functioning; to provide for a switch which shall be without the present dangers resultant from the installations of frogs, points, or guard-rails, with the spaces which necessarily exist between them, and which admit either of the entry therein of foreign substances to clog or obstruct, or which may catch the feet of the unwary.

The invention consists in certain novel features of construction of the several parts involved, operating as a frogless, pointless switch, and in the combination of those several elements in their interaction to produce such result, as hereinafter shown and described, and set forth in the accompanying claims.

Like reference characters refer to the same elements throughout. Figure 1 is a plan view of a switch embodying my invention in a modified form. Figure 2 is a fragmentary plan view of the hinge end of a rail. Figure 3 is a section on line 3—3 of Figure 2. Figure 4 is a section on line 4—4 of Figure 1. Figure 5 is a broken plan view of a tie-plate. Figure 6 is a detail view of the crossing arrangement. Figure 7 is a section on line 7—7 of Figure 6. Figure 8

is a plan view of a switch embodying my invention in complete form. Figure 9 is a detail of a bridle-rod member. Figure 10 is a detail plan view of a stop-device. Figure 11 is the same in elevation. Figure 12 is a section on line 12—12 of Figure 8. Figure 13 is a longitudinal section of a tie-plate.

Figure 1 is shown merely to illustrate how the device may be adapted to existing installations. Figure 8 shows the device in its fullest development, and is the one to which reference is hereinafter exclusively made.

In describing my invention in detail,

A A' are permanent rails of a main track-way. B B' are permanent rails of a switch-way, adjacent thereto. C C', etc., are ordinary cross-ties, in place, of varying lengths, as required for the proper installation of the switch and device. D is the head-block of the switch, and should be much longer than the others, as indicated by the dotted lines in Figure 8, so as to form a rest and support for the pivot-points, o o', of the connecting parts between the parallel members of the double bridle of the device. E E' F are the movable rail-sections, which, as stated, are part of the main trackway, but, by construction and adjustment, adaptable of movement into proper alignment in the switchway, and thereby completing it. In the operation of the device, this is accomplished by drawing these sections back and forth upon their hinge-ends, as pivots, from the positions shown by the solid lines in the main trackway, to those shown by the dotted lines in the switch-way, in Figure 8. G G' are parallel members of the double bridle effecting the foregoing movements of these moving sections. Of these members, G is shown as attached to two of the sections, and G' to the other one. These attachments are pivotal, and are designed to allow proper play of the parts during the movement described. By this arrangement, the two sections attached to G move simultaneously in the same direction, and their relative positions are meanwhile sustained by the operation of rods J J', etc., hereafter mentioned. H H' are connecting means between the parallel members of the bridle, the points of attachment to G and G' being at the ends thereof, indicated at k l m and n. I is the connecting means between the double bridle, above described, and a switch-

105

115

throw, in any form. $J J'$ are rods, already mentioned, attached adjustably between the two parallel similarly moving rail-sections $E E'$, designed, as stated, to assist in supporting their relative positions during their movements. K is any switch-throw to which the device is connected as indicated. $a a' b$ are fish-plates, angle-irons, or modified rail-supports, employed at hinge points of the rail-sections, and attached as already described, not only to fasten and hold the parts in place, but also, through the employment of spring-washers, or similar means, at the points of attachment, to admit of a swinging movement, through a short fixed and determined arc. The kind of fastening selected for use at any given point is wholly dependent upon what is deemed most efficacious to function properly under the circumstances there existing. $c c' d d' e e'$, etc., f , are, respectively, tie-plates, set in the supporting cross-ties, and upon which the moving rail sections are either hinged, as to their fixed ends, or made to slide back and forth, as to their moving ends. $g g' h$ are spring-washers employed in the attachment and fastening of the fish-plates, angle-irons, or other supporting and fastening means, such as $a a' b$, so that there may be opportunity for the freedom of movement of the parts to accomplish the necessary passage of the moving rail-sections from one position to another, as already described. i indicates a flange space, to be provided, in case a support in the form of b is employed, to admit of the passage of the wheel flange. j is the attachment of I to the bridle of the device, through which means and attachment, motion is communicated to the rods or members of the bridle to cause them to operate as described. $k l m n$ are means of attachment between the respective parallel members of the bridle, and their connecting parts, already mentioned. These attachments may appropriately be made by bolts passing through both parts to be attached, and fastened by washer and nut, in which event, the bolt holes should be made over-size, or arced, to admit of the play necessary to effect the movement and adjustment of the parts, as described. $o o'$ are pivot points of the parts connecting the parallel members mentioned, and should be raised and supported upon the head-block D . q is the depression in the tie-plates, already mentioned, in which the moving ends of the rail-sections rest and move, as already described. As stated, the shoulders of these, and of all such depressions, are designed to prevent the parts moving beyond pre-determined points. $r r'$, etc., are stop-devices designed and disposed to assist in this result of preventing the moving parts from going too far in their passage to and fro. They are so designed and constructed as to raise

fixed obstructions as the rails pass in one direction, and to drop out of engagement, and allow free movement in the other direction. These devices are mounted upon the several cross-ties bearing tie-plates, and adjacent to the shoulders of the tie-plate depressions described. $s s'$ are the means of attachment of these devices to the ties. t is a stop provided to hold the device firm in its resisting position, when operating to stop further forward movement of the rail-section. u is a pivot upon which the movable part of the stop-device turns in its operation, in passing in and out of engagement with the rail-section. v is a movable part of the device. It is so constructed and arranged as to allow the rail and flange, below the head, to engage corresponding parts of the device, and, acting against the resistance of the pivot, u , and the stop, t , to prevent the rail-section passing further in that direction. w is the trip of the stop-device, whereby, when the rail is started in the opposite direction, by pressure upon the slanted edge of w , as shown, the moving part of the device is pressed, or drops, down below the level of the tie-plate, and allows the rail-section free passage. x is the depression in those tie-plates constructed for use at the hinge-ends, as already described. These depressions occur, as stated, in all tie plates. Those used at the hinge-ends of the device as a whole, bear a raised part, y , shown in the drawings as a knob, or semi-sphere, designed, as already stated, to enter a correspondent hole, or depression, created in the bottom of the rail-section, at an appropriate point near its end.

As already stated, the device can be operated by any switch-throw, after the proper attachment has been made, as indicated. The operation of the device is as follows. When the switch-throw is operated, with the intention of opening the switch, the movable rail-sections being then a part of the main track-way, as shown by the solid lines in Figure 8, the pull of the throw, through the attachment I , is communicated to the device by the connection of I to G at j . This draws G into the position shown by the dotted lines in Figure 3. And, as G is attached, as described, to both E and E' , these are likewise carried in the same direction, and assume the positions shown by the dotted lines in the same figure. Simultaneously, motion is likewise, through the attachments already described, communicated to the connected parts, $H H'$, which, fulcrumed upon their pivots, $o o'$, carry the parallel member of the bridle, G' , in the direction opposite to that taken by its fellow, G , until it assumes the position also shown by dotted lines in Figure 8, and, inasmuch as G' is attached, as described, to rail-section F , that element of the device is likewise carried into its new

position, disclosed by the dotted lines in the switchway in the same figure. E E' and F have now all become parts of the switchway, and it is complete and ready for use.

- 5 The tie-plates, with their appropriate shoulders, as described, are so disposed and arranged that at this time, the movable rail-sections are in complete engagement with them, and further movement in that direction is impossible, while this result is still further assured by the coincident action of the stop-device, disposed and arranged as already described. When it is desired to close the switch, if the switch-throw is turned 10 back, action of the parts, the reverse of that above described, occurs, and all parts resume their former position, and E E' and F are again elements of the main trackway. And these results are entirely accomplished, with 15 certainty and safety, and without, as will be noted, the intervention of any additional or auxiliary rails, guard-rails or frogs.

While I have shown and described specific forms of construction of certain of the 20 parts herein, I do not limit myself to them, and expressly reserve the right to make any and all changes within the scope of the principles disclosed in the invention.

My claims are:—

- 30 1. In trackway switches, the construction of sections of the main trackway, adaptable to be carried by an attached pair of connected and interacting parallel members moving in opposite directions, into position 35 as elements of a completed switch-way from the main track, without additional or auxiliary rails, guard-rails or frogs, substantially as described.
2. In trackway switches, the construction 40 of appropriate sections of the main trackway, hinged at one end but slidably adjusted at the other, together with a pair of connected, interacting, oppositely-moving parallel members designed to move the free ends 45 of such sections out of alignment in the

main trackway and into position in an adjacent switch, so as to form a completed switch-way, wholly without additional or auxiliary rails, guard-rails or frogs, substantially as described. 50

3. In trackway switches, the combination of cross-ties, a head-block, an appropriate number of sections of a main trackway, so constructed as to be hinged at one end but free to slide from side to side, through pre-determined arcs, at the other, of appropriately designed plates, disposed upon the cross-ties, to receive and support the ends of such sections, of two parallel, interacting, oppositely-moving members appropriately 55 attached to and carried by the respective moving sections of the main trackway, and of means of communicating motion from a switch-throw to these parallel members, substantially as described. 60

4. In trackway switches, the combination of cross-ties, a head-block, an appropriate number of sections of a main trackway, so constructed as to be hinged at one end but free to slide through pre-determined arcs 70 at the other, of appropriate stop-devices disposed on the sides of the cross-ties at the ends of these arcs, of appropriately designed plates disposed upon the cross-ties to receive and support the ends of such sections, of two parallel, connected, oppositely-moving members appropriately attached to and carried by the respective moving sections of main trackway, and of means of communicating motion from a switch-throw 75 to these parallel members, substantially as described. 80

In witness whereof, I have hereunto affixed my signature in the presence of two witnesses.

MICHAEL WALSH.
